UNITED STATES PATENT OFFICE

2,457,888

STRAINER FOR PUMP JACKS

Edward P. Grime, Los Angeles, Calif.

Application April 10, 1945, Serial No. 587,540

3 Claims. (Cl. 210—164)

1

My invention relates to strainers for pump jacks, and among the objects of my invention are:

First, to provide a strainer which is interposed between the reservoir and working cylinder of a pump jack in such a manner that it may be readily removed for cleaning or replacement.

Second, to provide a strainer equipped pump jack which is simple of construction and compactly arranged.

With the above and other objects in view, reference is directed to the accompanying drawings, in which:

Fig. 1 is a side elevational view of a pump jack equipped with my strainer.

Fig. 2 is an enlarged fragmentary sectional view thereof taken through 2—2 of Fig. 1, showing the strainer in position.

Fig. 3 is a transverse sectional view taken through 3—3 of Fig. 2.

Fig. 4 is an enlarged side elevational view of the strainer, removed from the pump jack.

A hydraulic jack which is adapted to incorporate my strainer, includes a relatively flat base structure 1, which supports a reservoir inner shell 2 and a reservoir outer shell 3 defining an annular reservoir 4. Within the inner shell 2 is mounted a cylinder liner 5 which contains a piston 6.

The base structure is provided with a laterally directed ledge 8 having an internally threaded socket 9 which receives a pump unit 10. The pump unit includes an adapter fitting 11 intended to screwthread into the socket 9 and containing an intake port 12 and an outlet port 13 controlled by suitable ball check valves. The fitting supports the cylinder 14 of the pump unit containing a suitable piston (not shown) and from which extends a piston rod 15. A suitable handle 16 is provided for operating the piston rod 15.

The intake port 12 is connected to a reservoir 4 by a reservoir passage 17. The outlet port 13 is connected with the interior of the cylinder liner 5 by a jack cylinder passage 18. The passages 17 and 18 extend under the socket 9.

The passage 17 is counterbored as indicated by 19 and such counterbore extends radially outwardly to the extremity of the ledge 8. Port 12 continues through the bottom of the socket 9 and intersects the side wall of the counterbore 19. The outer portion of the counterbore is threaded to a depth beyond the intersection of the port 12 and is adapted to receive a strainer unit 20.

The strainer unit includes a stem 21 having two threaded portions 22 and 23 separated by the

stem 21 which is smaller than the threaded portions and cooperates with such portions to provide an annular chamber 24. When the strainer unit is fitted in the counterbore the threaded portions are located at opposite sides of the port 12 with the chamber 24 in registry therewith. A socket 25 intersects the inner end of the stem 21 and communicates with the chamber 24 by means of radial ports 26. A tubular strainer element 27, preferably formed of closely woven wire mesh closed at one end, is fitted by its other or open end over the inner extremity of the stem 21. The strainer element may be soldered or press fitted or otherwise secured to the stem so that it may be inserted or removed as a unit therewith. The outer end of the stem 21 is provided with a head 28 and gasket which sealingly engages the outer end of the counterbore.

Fluid from the reservoir passes through the strainer element 27 into the socket 25 through ports 26 around the chamber 24 and into the intake port 12. The inner set of threads 22 need not be fluid tight for in actual practice the normal clearance between the mating portion of the threads provides a bypass which is more restricted in area than the openings in the strainer unit.

In the structure shown, the pump unit is a single acting pump, and a relief valve (not shown) is employed for returning fluid from the cylinder 5 to the reservoir 4. Because of the location of the strainer, it is readily accessible.

Many other embodiments of the invention may be resorted to without departing from the spirit of the invention.

I claim:

1. A removable strainer unit for pump jacks wherein a base structure is provided with a passageway forming in part a strainer cavity open at its outer end and intersected intermediate its ends by a lateral port, the walls of said cavity being screw-threaded from their outer ends inwardly to a point beyond said lateral port, said strainer unit comprising: a stem having spaced screw-threaded portions, said stem being reduced in diameter between said screw-threaded portions and cooperating therewith to form an annular channel; a head at one end of said stem forming a shoulder and adapted to seat against said base structure at the outer end of said strainer cavity, and said screw-threaded portions fitting the screw threads of said strainer cavity on opposite sides of said lateral port when the stem is screwed therein; said stem having a socket 55 extending into its end remote from said head and

having lateral openings communicating between said socket and the annular channel; and a strainer element secured to said stem and extending from the socket end thereof.

2. A strainer unit for pump jacks wherein the pump jack has a strainer cavity connecting a coaxial and a lateral passage, the walls of said cavity being screw-threaded in the region of said lateral passage and a sealing face at the outer end of said cavity, said strainer comprising: a stem having a head at one end forming a shoulder adapted to seat against said sealing face and a socket at its other end, the stem also having axially inner and outer screw-threaded portions, said stem being of smaller diameter than said threaded portions in the region therebetween and cooperating with said portions to provide an annular chamber on opposite sides of said lateral passage; said annular chamber adapted to occupy a position in registry with said lateral passage and said stem having ports communicating between said socket and said annular chamber, said screw-threaded portions fitting the screw threads of said cavity on opposite sides of said lateral passage; and a strainer element covering the socket end of said stem and continuing axially therefrom.

3. A strainer unit for insertion in a screw-threaded counterbore communicating between an axially directed passage continuing from its inner end and a lateral passage intermediate its ends, the outer end of said counterbore being

5 open, the screw-threaded portion of said counterbore being connected intermediate its extremes by said lateral passage, said strainer unit comprising: a stem sealingly engageable with the walls surrounding the outer open end of said counterbore, said stem including spaced sets of screw threads, said stem being reduced in diameter between said screw threads and cooperating therewith to form an annular chamber adapted to communicate with said lateral passage when said sets of screw threads fit the screw threads of said counterbore at opposite sides of said lateral passage, said stem also being bored to form a passage communicating between its inner end and said annular chamber; and a tubular strainer closed at one end and secured by its other end to said stem whereby upon insertion of said stem in said counterbore a strainer interrupted passageway is formed between said axial passage 10 15 20 and said lateral passage.
